(57) **CLAIM**

The ornamental design for an electric spin scrubber, as shown and described.

DESCRIPTION

FIG. 1 is a front, right and top perspective view of an electric spin scrubber, showing my new design;

FIG. 2 is a rear, left and bottom perspective view thereof;

FIG. 3 is a front view thereof;

FIG. 4 is a rear view thereof;

FIG. 5 is a right side view thereof;

FIG. 6 is a left side view thereof;

FIG. 7 is an enlarged top plan view thereof;

FIG. 8 is an enlarged bottom plan view thereof;

FIG. 9 is an enlarged detail view of portion 9 encircled in FIG. 1; and,

FIG. 10 is an enlarged detail view of portion 10 encircled in FIG. 2.

The broken lines shown in the drawings illustrate portions of the electric spin scrubber that form no part of the claimed design.

(Continued)

The dot-dash broken lines depict the boundaries of the enlargements that form no part of the claimed design.
